UNITED STATES PATENT OFFICE.

FRANKLIN S. MCKENNEY, OF DETROIT, MICHIGAN, ASSIGNOR OF ONE-HALF
TO J. M. LONGYEAR, OF MARQUETTE, MICHIGAN.

DESIGN FOR A FASTENING.

SPECIFICATION forming part of Design No. 26,583, dated February 2, 1897.

Application filed December 9, 1895. Serial No. 571,594. Term of patent 14 years.

To all whom it may concern:

Be it known that I, FRANKLIN S. MCKENNEY, a citizen of the United States, residing at Detroit, county of Wayne, State of Michigan, have invented and produced a new and original Design for a Fastening; and I declare the following to be a full, clear, and exact description of the same, reference being had to the accompanying drawings, which form a part of this specification.

In the drawings, Figure 1 is a view in perspective disclosing my invention, the prongs being turned downward. Fig. 2 is a view in perspective having the prongs turned upward. Fig. 3 is a plan view from the side from which the prongs project.

My design relates to a fastening having a head and two prongs projecting essentially at right angles from the head, at opposite extremities thereof. The head A is of oblong or elliptical marginal outline and is made flat on both of its two surfaces. Toward opposite ends of the oblong head project the prongs a a from one of the surfaces thereof, said prongs being thus separated throughout one from the other. The prongs are made tapering from the point toward the base thereof,

the base of the prongs immediately adjacent to the head being broader and of heavier appearance than the remainder of the prongs. 30 The prongs at their base adjacent to the head are also each formed with an inward-projecting curve on their adjacent surfaces, the curves of the two prongs extending inward the one toward the other and toward the center of the head, as shown at a'. 35

The leading features of my design relate to the marginal outline of the head, the same being of oblong or elliptical form, the head being also flattened on its two surfaces, and 40 to the form of the prongs and the inward curvature thereof at their base, the prongs projecting from the opposite extremities of the head.

What I claim is—

The design for a fastening as herein shown and described.

In testimony whereof I sign this specification in the presence of two witnesses.

FRANKLIN S. MCKENNEY.
